UNITED STATES PATENT OFFICE

110,177

DESIGN FOR A TRAY OR SIMILAR RECEPTACLE

Paul S. Donchian, Hartford, Conn.

Application August 2, 1937, Serial No. 70,779

Term of patent 14 years

To all whom it may concern:

Be it known that I, Paul S. Donchian, a citizen of the United States, residing at Hartford, in the county of Hartford and State of Connecticut, have invented a new, original, and ornamental Design for a Tray or Similar Receptacle, of which the following is a specification, reference being had to the accompanying drawing, forming part thereof.

Fig. 1 is a perspective view of a tray or similar receptacle showing my new design;

Fig. 2 is a side elevation thereof;

Fig. 3 is a top plan thereof; and

Fig. 4 is a bottom plan thereof.

The dominant characteristics of the present de-

sign reside in a tray or similar receptacle having a border-rim formed of a series of elements, each of which may be defined as composed of a pentagonal pyramid and a triangular prism, one of the triangular faces of each of the pentagonal pyramids coinciding with one of the triangular faces of its complemental triangular prism, and the pentagonal bases of the said pyramids forming an outwardly-and-upwardly-sloping inner border-rim surface.

I claim:

The ornamental design for a tray or similar receptacle, substantially as shown and described.

PAUL S. DONCHIAN.
